Letters Patent No. 2471. Dated Sept 25. 1866.

Design for a Label

The Schedule referred to in this Letters Patent and making part of the same.

To all whom it may concern.

Be it known that A. A. Miles of the City of Winona in the County of Winona in the State of Minnesota, have invented and secured a Design for a Label of which the following is a full, clear and exact description, reference being had to the accompanying Specimen making a part of this Specification, and to the letter of reference marked thereon.

The border A, is composed of double lines, being rectangular except at the top where it is arched or curved. The outer line is heavier than the inner one and both having an ornamental flower piece, on each side and at the bottom. Another upper corner, there are also similar ornaments.

D, others again are shown at B, E, and C, the first being just over the word "Minisian", which is underlined the upper half part of the border, whilst the two latter are on the sides of a medallion, likeness of a female, at the bottom of this there is still another small flower ornament I, — Again, still below this is the word "Hair", on a black ground having a border J, around it. Below this comes the word "Dressing" in ornamental letters under the desk somewhat like the word "Minisian" before mentioned, the letters of which are more ornamental or fanciful.

Beneath this word "dressing" follows ordinary printed matter describing the use of the Hair dressing - pieces, by whom, and where prepared &c.

Having thus described, my invention, what I claim as my invention and desire to secure by Letters Patent of the United States is: The Design for a Label as shown and described.
